HAIR GROOMING PREPARATION

Robert James Mehaffey, River Edge, N. J., assignor to Colgate-Palmolive Company, a corporation of Delaware

No Drawing. Application July 10, 1953,
Serial No. 367,345

8 Claims. (Cl. 167—87)

The present invention relates to an aqueous-alcoholic hair grooming preparation and more particularly to an aqueous-alcoholic hair grooming preparation of the type containing in combination with other ingredients a lower alkoxypropoxy lower alkylene glycol and an organic ester.

It is an object of the present invention to provide an aqueous-alcoholic hair grooming preparation possessing improved properties that will produce improved effects when properly used.

It is a still further object of the present invention to provide a novel aqueous-alcoholic hair grooming preparation that contains in addition to other ingredients a lower alkoxypropoxy lower alkylene glycol in combination with an organic ester.

Other and further objects of the present invention will become apparent from a consideration of the following description.

The novel aqueous-alcoholic hair grooming preparation of the present invention contains a lower alkoxypropoxy lower alkylene glycol with an organic ester compounded with other ingredients which give the composition suitable properties for the application to the hair, e. g., in the form of a liquid.

Among the lower alkoxypropoxy lower alkylene glycols which can be combined with the organic ester in an aqueous-alcoholic solution is butoxypropoxypropylene glycol. Butoxypolyoxypropylene glycol confers particularly suitable properties on the composition and therefore is preferably employed in the present invention. The lower alkoxypropoxy lower alkylene glycol serves the main function in the composition of holding the hair in place. It also imparts a certain amount of luster to the hair.

It has been determined that a lower alkoxypropoxy lower alkylene glycol in sole combination with an aqueous-alcoholic solvent medium provides a clear, stable solution only at temperatures above about 75° F. At lower temperatures a mixture of these ingredients alone becomes cloudy and loses its desirable clear appearance.

It has now been discovered that the admixture of an organic ester of a polyoxyalkylene glycol and a long chain fatty acid with a lower alkoxypropoxy lower alkylene glycol and an aqueous-alcoholic solvent medium results in the formation of a hair preparation which is a clear, stable solution at temperatures below 75° F. and even at temperatures as low as about 35° F.

A typical example of an organic ester of a polyoxyalkylene glycol and a long chain fatty acid suitable for use in accordance with this invention is the monoester obtainable by reacting a polyoxyethylene glycol having an average molecular weight of about 400 with the mixed fatty acids obtained from coconut oil.

If desired, an organic ester formed from an alkylene glycol and a long chain fatty acid also may be employed in the present composition for the purpose of adjusting the consistency of the overall mixture and to give a more glossy appearance to the hair. A specific example of such an ester is propylene glycol monolaurate. This

2

compound is a monoester of propylene glycol and lauric acid.

Any of the long chain fatty acids may be employed to form the above-mentioned esters and it is within the purview of the present invention that the carbon atom content of the fatty acids may range from about 8 to about 24, and preferably from about 12 to about 18. Examples of fatty acids that may be employed to form the esters above referred to are lauric, palmitic, myristic, stearic, oleic and the mixed fatty acids obtained from coconut oil.

Other compounds, in addition to butoxypolyoxypropylene glycol and the organic ester or esters, may be included in the aqueous-alcoholic composition, such as rubefacients, germicidal agents, perfume oil and coloring.

The rubefacients are added to the composition to give a tingling and stimulating effect to the scalp. Typical examples of the rubefacients employed are tincture of capsicum, menthol, turpentine and mustard oil.

The germicidal agent is employed in the composition to destroy the microorganisms customarily found on the hair and scalp and thereby prevent development of the common diseases of the scalp. The type of germicidal agent which proved most satisfactory was a cationic quaternary ammonium compound such as cetyl dimethyl benzyl ammonium chloride or cetyl isopropyl isobutyl benzyl ammonium chloride. More particularly, a 50% solution of cetyl dimethyl benzyl ammonium chloride was used. It should be understood, however, that it is within the purview of this invention to use other germicidal agents, such as 0.5% of lauroylcolaminoformylmethyl pyridinium chloride.

As referred to hereinbefore the hair grooming preparation is one containing alcohol. The alcohol not only acts as a carrier for the remaining constituents in that it increases their solubility but acts also to give a warming effect to the scalp. Among the alcohols which may be used are ethyl, propyl, isopropyl, butyl and isobutyl, i. e., the lower liquid aliphatic alcohols.

Water, perfume oil and coloring are also added to the composition, the water being added to minimize the amount of alcohol required while the perfume oil and the coloring are added to give the composition a pleasant smelling effect and the color desired.

In determining the proportions of each compound to give the desired results, it was found that the proportion of the lower alkoxypropoxy lower alkylene glycol employed should be maintained preferably between 5 to 30%, that the proportion of the ester formed from an alkylene glycol and a long chain fatty acid should be maintained preferably between 0.1 to 5.0%, that the proportion of the ester formed from a polyoxyalkylene glycol and a long chain fatty acid should be maintained preferably between 0.1 to 5.0%, that the total amount of rubefacient employed should be maintained preferably between 0.1 to 5.0%, that the proportion of germicidal agent present be maintained preferably within a range of 0.1 to 5.0%, that the proportion of alcohol be maintained preferably between 40 to 60%, and that the proportion of water be maintained within a range of about 20 to 30% with the remaining constituents being coloring and perfume oil.

To illustrate the general process of preparing a hair grooming preparation of this type all of the materials in this preparation with the exception of water are weighed into a vessel. The water is weighed in a separate vessel and then added to the first vessel with agitation. The resultant product is then chilled.

Having described the present invention in its broader aspects, a more detailed example of the composition in accordance therewith is now given in order to assist in a better understanding of its various ramifications, it being

understood that this is included herein for purposes of illustration rather than limitation. Percentages are by weight throughout the specification and claims unless otherwise indicated.

Example

Butoxypolyoxypropylene glycol	percent	20.0
Propylene glycol monolaurate	do	1.10
Monoester of polyoxyethylene glycol having an average molecular weight of about 400 and the mixed fatty acids obtained from coconut oil	percent	2.00
50% solution of cetyl dimethylbenzyl ammonium chloride	percent	1.00
Tincture of capsicum	do	0.50
Menthol	do	0.50
Ethyl alcohol SD 40	do	51.25
Perfume oil	do	0.40
Water	do	23.25
Color	Q. S.	20

Summarizing, the present invention is based upon a new composition which comprises a lower alkoxypropoxy lower alkylene glycol and an organic ester or esters in combination with an aqueous-alcoholic solvent medium to form a highly effective hair preparation.

While the invention has been described in terms of a preferred embodiment thereof, it is to be understood that considerable variations from the details disclosed might be made without departing from the true scope and spirit of the invention. Accordingly, the invention is to be limited only by the claims set forth hereinafter.

What is claimed is:

1. A hair grooming preparation comprising a clear aqueous-alcoholic solution of a lower alkoxypropoxy lower alkylene glycol for maintaining the hair in place, and means for extending downwardly the temperature range within which the preparation is in the form of a clear, stable solution, said means comprising an organic ester of a polyoxyalkylene glycol and a long chain fatty acid.

2. A hair grooming preparation comprising a clear aqueous-alcoholic solution of a lower alkoxypropoxy lower alkylene glycol and an organic ester of a polyoxyalkylene glycol and a long chain fatty acid.

3. A hair grooming preparation comprising a clear aqueous-alcoholic solution of a lower alkoxypropoxy lower alkylene glycol, and an ester of a polyoxyalkylene glycol and a long chain fatty acid having a chain length of from about 8 to about 24 carbon atoms.

4. A hair grooming preparation comprising a clear aqueous-alcoholic solution of butoxypolyoxypropylene glycol, and a monoester of a polyoxyethylene glycol hav-

ing an average molecular weight of about 400 and the mixed fatty acids obtained from coconut oil.

5. A hair grooming preparation comprising a clear aqueous-alcoholic solution of about 5 to about 30% of a lower alkoxypropoxy lower alkylene glycol, about 0.1 to about 5.0% of an ester of alkylene glycol and a long chain fatty acid having a chain length of from about 8 to 24 carbon atoms, and about 0.1 to about 5.0% of an ester of a polyoxyalkylene glycol and a long chain fatty acid having a chain length of from about 8 to 24 carbon atoms.

6. A hair grooming preparation comprising a clear aqueous-alcoholic solution of a lower alkoxypropoxy lower alkylene glycol, an ester of an alkylene glycol and a long chain fatty acid, an ester of polyoxyalkylene glycol and a long chain fatty acid, rubefacients, and a germicidal agent.

7. A hair grooming preparation comprising 5 to 30% of butoxypolyoxypropylene glycol, 0.1 to 5.0% propylene glycol monolaurate, 0.1 to 5.0% of the monoester of polyoxyethylene glycol having an average molecular weight of about 400 and the mixed fatty acids obtained from coconut oil, 0.5% of tincture of capsicum, 0.5% menthol, 0.1 to 5% cetyl dimethylbenzyl ammonium chloride, 40 to 60% ethyl alcohol, and 20 to 30% water.

8. A hair grooming preparation consisting essentially of 20.0% butoxypolyoxypropylene glycol, 1.10% propylene glycol monolaurate, 2.00% of the monoester of polyoxyethylene glycol having an average molecular weight of about 400 and the mixed fatty acids obtained from coconut oil, 0.5% tincture of capsicum, 0.5% menthol, 1.00% of a 50% solution of cetyl dimethylbenzyl ammonium chloride, 51.25% ethyl alcohol, 0.5% perfume oil and 23.25% water.
